UNITED STATES PATENT OFFICE.

WILLIAM MILNER AND WILLIAM WILSON, OF LONDON, ENGLAND, ASSIGNORS
TO THE SPEED INDICATOR COMPANY, LIMITED, OF SAME PLACE.

SPEED-INDICATOR.

SPECIFICATION forming part of Letters Patent No. 611,265, dated September 27, 1898.

Application filed December 20, 1897. Serial No. 662,590. (No model.)

To all whom it may concern:

Be it known that we, WILLIAM MILNER and WILLIAM WILSON, subjects of the Queen of Great Britain, residing at London, England, have invented certain new and useful Improvements in Speed-Indicators, of which the following is a full, clear, and exact description.

The invention relates to that class of speed-indicators wherein the speed is indicated by the position occupied by a hand or pointer traveling round a scale and in which a current of air from a fan-blower acts against a disk, blade, or plate to give motion to the said hand or pointer in one direction, while a spring acts to move the hand or pointer in the contrary direction.

Our invention relates to an improved and simple construction of parts whereby the fan-blower can be rotated in either direction and the current of air therefrom caused to act upon the disk, blade, or plate always in the same direction, thereby obviating the necessity for any intermediate gearing between the main or driving spindle of the indicator and the fan.

Our invention is illustrated in the accompanying drawings, in which—

Figure 1 is a sectional elevation, Fig. 2 a vertical cross-section, and Fig. 3 a cross-section of parts drawn on the line 3 3 of Fig. 1, of a speed-indicator constructed according to our invention.

We prefer to form the frame or case *a* in several parts, as shown, for facility of manufacture.

In carrying our invention into effect we form, preferably in the lower part of the frame *a*, a fan-blower chamber *a'*, in which we mount a fan *b*, of form to act equally well in either direction. The sides of the said chamber *a'* are provided with outwardly-projecting bearings *a²* to receive the fan-blower shaft *b'*, fitted with a driving-pulley *b²*, and each bearing *a²* is fitted with a suitable lubricator *a³*. The bearings *a²* are carried by outwardly-projecting cylindrical chambers *a⁴*, closed on the outer ends and extending inward to within a short distance of the boss of the fan-blower *b*, and the outer portions of said cylindrical chambers *a⁴* are perforated on the under side,

as shown at *a⁵*, to permit of free entry of air into the fan-blower chamber *a'* and at the same time prevent the accidental entry of foreign matter.

The fan-blower chamber *a'* is generally of 55 cylindrical form, and the peripheral outlet is formed of outwardly-inclined walls *a⁶*, joining the cylindrical portion and directed toward each other. This outlet communicates with and is hermetically connected to a conducting-space *c*, having all its walls inclined toward an opening *c'*, which delivers the current of air to an annular chamber *d*, within which the disk, blade, or plate *e* works and closely fits without touching its walls. This 65 annular chamber *d* is closed around its outer periphery and sides, except that its periphery has an inlet-opening *d'* and an outlet-opening *d²* fitting closely against the aforesaid air-conducting space *c*.

From the inlet-opening *d'* an inclined wall *d³* extends entirely across the annular chamber *d* to conduct the current of air toward the disk, blade, or plate *e* in the required direction and at the same time separate the inlet-aperture *d'* from the outlet-aperture *d²*, which latter is formed in the rear side of the annular chamber close to the inlet-aperture. The periphery of the annular chamber *d* fits closely a cylindrical chamber *a⁷* in the frame *a*; but 80 such annular chamber *d* does not extend to the rear of said cylindrical chamber *a⁷*, but leaves an air-space, into which the air passing away from the annular chamber *d* is received and from which it passes by perforations *a⁸* 85 into a space formed in an external cap or cover *f* and thence away to the outer air through a downwardly-directed slit or opening *f'* in the rim of said cap *f*.

The arm *e'* of the disk, blade, or plate *e* is 90 mounted on the spindle *g*, carrying the hand or pointer *g'*, and said arm *e'* passes through and travels in a narrow slit *d⁴* formed in the inner periphery of the annular chamber *d*. The said annular chamber *d* is carried by the 95 front plate *h* of the indicator, and the spindle *g* passes through such plate *h* and a divided and figured face-plate *i*, and the hand or pointer *g'* is mounted on the outer end of said spindle *g*.

The current of air created by the fan-blower will act upon the disk, blade, or plate *e* to drive it in one direction against the action of a spring *j*, which latter will tend to return said disk, blade, or plate *e* toward its starting-point.

Having thus fully described our invention, what we claim, and desire to secure by Letters Patent, is—

- 10 1. In a speed-indicator, the combination of a frame, a fan-blower chamber within said frame provided with downwardly-directed inlet-openings, a fan-blower, of shape to act equally well in both directions of rotation,
- 15 2. mounted in said chamber, an outlet from the fan-blower chamber having inclined walls directed toward each other, a conducting-space hermetically connected to said outlet having inclined walls leading to an inlet-opening in
- 20 the periphery of a cylindrical chamber in the frame, an annular chamber fitting closely the periphery of said cylindrical chamber, an inlet-opening in the periphery of the annular chamber communicating with the inlet-opening in the cylindrical chamber, an outlet-opening in the rear side of said annular chamber communicating with a space in the cylindrical chamber, a disk, blade or plate, working within the annular chamber and mounted
- 25 3. on a spindle carrying the indicating-hand, an external chamber communicating with the rear of the cylindrical chamber by holes in rear wall of the latter, and a downwardly-directed outlet-opening in said external chamber, all substantially as herein set forth and for the purpose stated.
- 30 4. 2. In a speed-indicator, the combination of

a fan-blower chamber having protected inlet-openings, a fan-blower within said chamber capable of acting equally well in both directions, an outlet from said fan-blower chamber formed with walls inclined toward each other, and leading to an opening in a cylindrical chamber, an annular chamber fitting closely such cylindrical chamber and having in its periphery an inlet-opening communicating with the opening in the cylindrical chamber, a protected outlet from said cylindrical chamber, an outlet-opening in the rear of the annular chamber separated from the inlet-opening and communicating with a space in the cylindrical chamber, a disk, blade or plate, working within said annular chamber and operating the indicating-hand in one direction, and a spring acting in the contrary direction on said indicating-hand, all substantially as herein set forth.

3. In a speed-indicator, the combination of a fan-blower acting equally well in both directions, a channel conducting the current of air into an annular chamber, a disk, blade or plate, working in said annular chamber and closely fitting without touching the walls thereof and operating the indicating-hand in one direction, and suitably-protected air inlets and outlets, all substantially as herein set forth.

In testimony whereof we affix our signatures in presence of two witnesses.

W. MILNER.
W. WILSON.
